(57) **CLAIM**

The ornamental design for a wireless earphone, as shown and described.

DESCRIPTION

FIG. 1 is a perspective view of a wireless earphone showing the new design;

FIG. 2 is a top plan view thereof;

FIG. 3 is a side elevational view thereof;

FIG. 4 is a bottom view thereof;

FIG. 5 is a side elevational view thereof;

FIG. 6 is a top view thereof; and,

FIG. 7 is a bottom plan view thereof.

The broken lines illustrate portions of the wireless earphone that form no part of the claimed design.

1 Claim, 7 Drawing Sheets
